UNITED STATES PATENT OFFICE.

WILLIAM DAVID QUIGLEY AND JOSEPH HENRY GAY, OF NEWARK,
NEW JERSEY.

SHARPENING DEVICE FOR MOVING KNIFE-BLADES.

SPECIFICATION forming part of Letters Patent No. 747,476, dated December 22, 1903.

Original application filed February 3, 1902, Serial No. 92,449. Divided and this application filed November 12, 1902.
Serial No. 130,993. (No model.)

To all whom it may concern:

Be it known that we, WILLIAM DAVID QUIGLEY and JOSEPH HENRY GAY, citizens of the United States, and residents of Newark, Essex county, New Jersey, have invented a new and useful Improvement in Sharpening Devices for Moving Knife-Blades, of which the following is a specification.

This application is a division of our application, Serial No. 92,449, filed February 3, 1902, and relates more particularly to the construction and arrangement of the knife-sharpening devices employed in the leather-splitting machine disclosed in said application.

The invention consists in said construction and arrangement of said devices, as more particularly pointed out in the claims.

In the accompanying drawings, Figure 1 is a side elevation of the left-hand end of the leather-splitting machine described in our aforesaid application, showing our improved knife-sharpening devices in place. Fig. 2 is an enlarged detail view of the same end of the machine in side elevation with parts broken away to show more clearly the construction of the supports and adjusting devices for the rotary grinder. Fig. 3 is an enlarged detail view of the lower portion of the same end of the machine in front elevation with parts broken away for the purpose above stated. Fig. 4 is a section on the line *b b* of Fig. 3, taken in the direction of the arrow *b'*. Fig. 5 is a side elevation of the steel disk and its support. Fig. 6 shows the device for raising and lowering the lower frame *K*.

Similar letters of reference indicate like parts.

A is the table, supported on legs *B*. It carries at each end two similar side frames, one of which is shown at *C*. Between these frames is the truss-frame *G*, which carries the upper or spring roll *H* and swings on trunnions, one of which is shown at *E*. On the table *A* are two standards, one of which is shown at *J*, in which is journaled the lower truss-frame *K*, which carries the gage-roll *L*. The knife is an endless band *M*, which passes over wheels journaled at the ends of

the table, which wheels are rotated. One of said wheels *N* is positively driven, the other (not shown) is rotated by the knife-blade acting as a belt. The knife is placed so that its edge comes between the rollers *H L*. The free end of the hide is introduced between the drawing-in rolls *H L* and is carried by the rotation thereof, so that its advancing edge meets the edge of the moving knife *M* and is so split.

The main driving-pulley *Q*, Fig. 1, is on a short shaft which carries a straight pinion *Q'* (dotted lines) and a beveled pinion. (Not shown.) Pinion *Q'* engages with pinion *Q⁸* on the shaft of wheel *N*, and so rotates said wheel, and thus causes movement of the band-knife. The beveled pinion on the driving-shaft 65 through intermediate gearing (not shown) rotates the beveled pinion *Q⁹*. Pinion *Q⁹* engages with pinion *Q¹⁰* on shaft *Q⁸*, and from shaft *Q⁸* by suitable gearing both rolls *H* and *L* are driven.

All of the foregoing parts, together with the various adjusting devices of the machine, are fully described in our aforesaid application.

The shape of the knife *M* is shown in cross-section in Fig. 2—that is to say, it has one side beveled to form an edge with its opposite flat side, and as here arranged the flat side is underneath when the knife is acting on the hide. Inasmuch as the edge of the knife becomes dulled in use we provide means for constantly sharpening the same, while maintaining the angle of bevel with the flat edge unimpaired by the following devices: *V V'*, Figs. 1, 2, and 3, are brackets bolted on the under side of the table *A*. Between 85 said brackets extends a frame *V²*. At the lower inner portions of said brackets are inclined guide-channels *V³* to receive ribs *V⁴* on the frame *V⁵*. Said frame is supported by the screw *V⁶*, which is provided with adjusting-nuts *V⁷* above and below the curved upper member of frame *V⁵*. On the front side of frame *V⁵* are bolted journal-boxes *V⁸* for the shaft *V⁹*, and said shaft carries an emery-wheel *V¹⁰* and driving-pulley *V¹¹*. The emery-wheel *V¹⁰* is adjusted against the edge

of the blade M to grind the bevel by means of the screw V⁶, its position then being as in Fig. 2, and it is rotated by the belt V¹² on the driving-pulley, which belt leads from any suitable motor. The shaft V⁹ is threaded to receive a nut and disk V¹³, between which disk and the fixed disk V¹⁴ the emery-wheel is secured. In order to support the back of the blade and hold the edge up to the emery-wheel, a fixed table or ledge V¹⁵ (shown broken away in Fig. 3) is provided, over which the blade travels. Through an outer flange V¹⁶ of said table passes a screw V¹⁷, which bears against the back of the blade, as shown in dotted lines, Fig. 2. Said screw both supports the blade and serves to adjust it toward the emery-wheel. A jam-nut V¹⁸ is provided for holding the screw as adjusted. A steel disk W, Fig. 6, is disposed, as shown 20 in Fig. 1, so that the knife bears against its inclined under side. Said disk is pivoted by the adjusting-screws W' in the yoke W². Said yoke is pivoted in a bearing in the upper end of post W³, and said post is vertically adjustable in the fixed standard W⁴. The yoke W² is normally free to turn on its pivot. It may be clamped in position, if desired, by means of the set-screw W⁵. The disk and yoke can be raised and lowered by 25 raising or lowering the post W³ in standard W⁴, and said yoke is fastened in place as adjusted by means of the set-screw W⁶. When the yoke W² is not clamped, the spiral spring W⁷, attached to the upper adjusting-screw W' and to any fixed abutment, is employed 30 for bringing the under side of the disk W with regulated steady pressure against the blade. The object of the disk W is slightly to turn downward the extreme edge of the 40 blade in advance of the action of the grinding-wheel V¹⁰ upon it. This turned-over por-

tion is ground off by wheel V¹⁰, leaving the final edge true and straight.

We claim—

1. In combination with a longitudinally-movable knife-blade, a rotary grinder having its axis of rotation parallel to said blade and its circumferential periphery acting to produce a bevel thereon, and means for moving the said axis of rotation of said grinder in a 45 plane at right angles to the plane of said bevel, substantially as described.

2. In combination with a longitudinally-movable knife-blade a rotary grinder having 50 its axis of rotation parallel to said blade and its circumferential periphery acting to produce a bevel thereon, means for moving said blade in its own plane with reference to said grinder—and means for moving the axis of rotation of said grinder in a plane at right angles to the plane of said bevel, substantially as described.

3. The combination with a longitudinally-moving knife-blade, of the disk W, pivoted yoke W² therefor, supporting-rod W³ for said 55 yoke, and standard W⁴ receiving said rod, substantially as described.

4. The combination with a longitudinally-moving knife-blade, of the disk W and supporting-shaft therefor, pivoted yoke W², set-screws W' for adjusting said disk in said 60 yoke, supporting-rod W³ for said yoke and standard W⁴ receiving said rod, substantially as described.

In testimony whereof we have signed our 75 names to this specification in the presence of two subscribing witnesses.

WILLIAM DAVID QUIGLEY.
JOSEPH HENRY GAY.
